(57) **CLAIM**

The ornamental design for a wall mounted water heater, as shown and described.

DESCRIPTION

FIG. 1 is a front perspective view of one embodiment of a wall mounted water heater according to the present invention;

FIG. 2 is a front view;

FIG. 3 is a rear view;

FIG. 4 is a first side view;

FIG. 5 is a second side view;

FIG. 6 is top view;

FIG. 7 is a bottom view;

FIG. 8 is a front perspective view of another embodiment of a wall mounted water heater according to the present invention;

FIG. 9 is a front view;

FIG. 10 is a rear view;

FIG. 11 is a first side view;

FIG. 12 is a second side view;

FIG. 13 is top view; and,

FIG. 14 is a bottom view.

The broken lines shown in the drawings represent unclaimed portions and form no part of the claimed design.

1 Claim, 12 Drawing Sheets
